CLAIM

The ornamental design for a display screen with graphical user interface, as shown and described.

DESCRIPTION

The FIGURE is a front view of a display screen with graphical user interface showing our new design.

The peripheral dash-dot-dash lines illustrate a display screen or portion thereof and form no part of the claimed design. The dashed broken lines within the peripheral dash-dot dash lines illustrate portions of the graphical user interface which form no part of the claimed design.

UNITED STATES PATENT AND TRADEMARK OFFICE
CERTIFICATE OF CORRECTION

PATENT NO. : D1,039,543 S
APPLICATION NO. : 29/838032
DATED : August 20, 2024
INVENTOR(S) : Min Liu et al.

Page 1 of 1

It is certified that error appears in the above-identified patent and that said Letters Patent is hereby corrected as shown below:

On the Title Page

Item (72):

“(72) Inventors: Min Liu, San Francisco, CA (US);
Elizabeth Lin, San Francisco, CA (US);
Teo Connor, San Francisco, CA (US);
David Muro, San Francisco, CA (US)”

Should read:

--(72) Inventors: Min Liu, San Francisco, CA (US);
Elizabeth Lin, San Francisco, CA (US);
Teofila Connor, San Francisco, CA (US);
David Muro, San Francisco, CA (US)--

Signed and Sealed this
Fourteenth Day of October, 2025

John A. Squires
Director of the United States Patent and Trademark Office
